UNITED STATES PATENT OFFICE.

JOSEF HORVAT, OF SUPERIOR, WISCONSIN.

RAILWAY-RAIL JOINT.

1,145,992.

Specification of Letters Patent. Patented July 13, 1915.

Application filed March 8, 1915. Serial No. 12,733.

To all whom it may concern:

Be it known that I, JOSEF HORVAT, a subject of the Emperor of Austria-Hungary, residing at Superior, in the county of 5 Douglas, State of Wisconsin, have invented certain new and useful Improvements in Railway-Rail Joints, of which the following is a specification.

My invention relates to improvements in 10 joints and particularly to joints employed to connect the contiguous ends of railway rails.

The object of my invention is to so construct and arrange the connecting device 15 that the rails can be easily and quickly joined to or disconnected from each other without driving or withdrawing spikes, and to so clamp the rails in the joint that they will be securely and positively fastened to 20 each other when in their assembled position. This and other objects I accomplish as set forth in the following specification and as more particularly pointed out in the 25 claims, reference being had to the accompanying drawings in which a preferred embodiment or adaptation of the invention is shown.

In the drawings, Figure 1 is a top plan view of the contiguous terminal portions of 30 two railway rails with my improved joint clamped thereto; Fig. 2 is a transverse vertical section on line 2—2, Fig. 1; and Fig. 3 is a detached perspective view of the separate fish-plate.

25 In referring to the drawings in detail, like numerals, letters, characters, or symbols designate like or corresponding parts in the adaptation of my invention illustrated therein.

40 The rails shown are of the usual well-known form, each comprising a head 1, foot 2, and connecting web 3. The usual openings 4 in the webs of the rails are shown in dotted lines in Fig. 2.

45 My improved joint comprises a shoe in which the ends of the rails are fitted in longitudinal alinement, said shoe having a base 5, an integral fish-plate 6 extending from one side of said base, and a slotted enlargement 7 upon the opposite side of said base in the slot 8 of which the outer extremity of a clamping bar 9 is pivoted. The clamping bar 9 has a cam portion 10 against which one end of a substantially 50 flat spring 11 presses to maintain said bar in clamping position. The inner end of the

bar 9 is enlarged to form a holding plate 12 which contacts with the separate fish-plate 13. Both the integral fish-plate 6 and the separate fish-plate 13 are provided with inwardly-extending pins 14 which when the joint is in its rail-connecting position fit and lock in the openings 4 in the rails as shown in Fig. 2.

The clamping bar is provided with a suitable top recess 15 in which the end of a crow bar or other implement may be inserted for the purpose of lifting the clamping bar against the tension of the spring 11 and dismounting the device. By referring to Fig. 7, 2, it will be noted that the end edge 16 of the clamping bar is substantially flat and fits against the end wall of the slot 8 when the bar is in clamping position, thereby forming a strong and practically rigid support 7 for the separate fish-plate.

While I have illustrated and described a preferred form of construction for carrying my invention into effect, this is capable of a wide range of variation, alteration, 8 modification, and change without departing from the spirit of my invention. I, therefore, do not wish to be limited to the construction herein shown and described but desire to avail myself of all such variations, 8 alterations, modifications, and changes as fairly fall within the scope of the appended claims or may be construed to be within the scope thereof by invoking the doctrine of equivalents.

What I claim as my invention and desire to secure by Letters Patent is:

1. In a device of the class described, two rails having their contiguous ends in longitudinal alinement, and a joint for connecting the ends of said rails having a shoe in which said rails are fitted and comprising a base provided with a slot, two opposed fish-plates between which rails are clamped, and a clamping bar pivoted in the slot of the base.

2. In a device of the class described, two rails having their contiguous ends in longitudinal alinement, and a joint for connecting the ends of said rails having a shoe in which said rails are fitted and comprising a base provided with a slot, two opposed fish-plates between which rails are clamped, and a clamping bar having its outer extremity pivoted in the slot and its inner end bearing against one of the fish plates.

3. In a device of the class described, two

- 2
- rails having their contiguous ends in longitudinal alinement, and a joint for connecting the ends of said rails having a shoe in which said rails are fitted and comprising a base provided with a slot, two opposed fish-plates between which rails are clamped, a clamping bar pivoted in the slot in the base and a spring for normally maintaining said bar in clamping position.
- 10 4. In a device of the class described, two rails having their contiguous ends in longitudinal alinement, and a joint for connecting the ends of said rails having a shoe in which said rails are fitted and comprising
- a base provided with a slot, two opposed fish-plates between which rails are clamped, and a clamping bar having its outer extremity pivoted in the slot and its inner end bearing against one of the fish-plates, said bar having a recess for the insertion of a suitable lifting tool.
- In testimony whereof I have hereunto affixed my name in the presence of two witnesses.

JOSEF HORVAT.
